DESIGN FOR A GRILLE

Edward H. McCloud, Columbus, Ohio, assignor to
The Kinnear Manufacturing Company, Columbus, Ohio, a corporation of Ohio

Application November 22, 1940, Serial No. 96,733

Term of patent 14 years

To all whom it may concern:

Be it known that I, Edward H. McCloud, a resident of Columbus, in the county of Franklin and State of Ohio, have invented a new, original, and ornamental Design for a Grille, of which the following is a specification, reference being had to the accompanying drawing forming part thereof, wherein:

I claim:

The ornamental design for a grille, substantially as shown.

EDWARD H. McCLOUD.
